UNITED STATES PATENT OFFICE.

ROBERT W. GRAY, OF DEDHAM, MASSACHUSETTS, ASSIGNOR OF ONE-HALF OF HIS RIGHT TO GEORGE FROST, GEORGE H. FELPS, AND GEORGE A. FROST, OF SAME PLACE.

SHOULDER AND BACK BRACE.

SPECIFICATION forming part of Letters Patent No. 224,899, dated February 24, 1880.

Application filed January 2, 1880.

To all whom it may concern:

Be it known that I, ROBERT W. GRAY, of Dedham, county of Norfolk, State of Massachusetts, have invented an Improvement in Shoulder and Back Braces, of which the following description, in connection with the accompanying drawings, is a specification.

This invention relates to a combined shoulder and back brace adapted to be used instead of the corset to give shape to the back and at the same time act as a back-support, and with shoulder-straps connected therewith, to also serve as a shoulder-brace. With these parts I have also added an umbilical supporter and suitable attachments to support skirts and stockings.

Figure 1 represents one of my improved shoulder and back braces extended out flat, one of the shoulder-straps being partially broken away; and Fig. 2, a section taken through the shoulder-strap on the line *x x*.

This article of apparel is composed of two back-pieces, *a b*, suitably braced together by the lacing-cord *c*, and stiffened with bones or cane, as at *d e* in dotted lines, and such back part is curved or cut, as at *2 3*, to form part of an arm-scye, the other complementary part thereof, when the article is in use, being formed by the lower edges, *4*, of the shoulder-straps *f*, (shown as connected at their wider ends with the back parts *a b* by means of elastic straps *g*,) the free and preferably elastic ends *5* of the straps, to complete the arm-scyes, being engaged with the buckles or fastenings *h*, connected with the back-pieces *a b*.

The shoulder-straps at the parts *6*, where they bear against the front of the shoulder, are padded, as shown most clearly in Fig. 2, and the edge *7*, which is nearest the chest, is made thin and yielding, so as not to bear upon or cut into the chest or breast of the wearer.

The arm-scye, when the ends *5* are joined with buckles *h*, will be, it is obvious, elastic by reason of the straps *g* and *6*, and will yield to the shoulders as the arms are moved, and insure a snug but not too close fit.

Each piece *a b*, at its side edges, substantially midway between part *3* and the lower

end of the said pieces, has connected with it a strap, *i*, and the said straps are connected, 50 when the article is worn, with the buckles or fastenings *8* of the supporter *k*, which, as the straps *i* are placed, as in Fig. 1, bring the supporter in position to act as an umbilical supporter.

Supporter *k* is suitably stiffened by bones or otherwise.

At or near the lower ends of the back-pieces are buttons *l*, upon which to attach stocking-supporters *s*, of usual construction, and above 60 the buttons are shown suitable pins or fastenings *m*, from or by which to support skirts.

This article of apparel acts under a dress to shape the dress at back as well as a corset, but at front permits the lungs to expand, and 65 overcomes many of the objections inherent in corsets.

The pieces *a b*, to fit and shape them to the back near the hips, are provided with gores 10 10.

I claim—

1. The two back-pieces *a b*, provided with curved edges *2 3*, combined with the shoulder-straps connected therewith, and adapted, when joined with the back-pieces at both ends, to 75 form arm-scyes, substantially as described.

2. The back-pieces *a b*, laced together, and the shoulder-straps, combined with an attached umbilical supporter, substantially as described.

3. The back-pieces *a b*, provided with gores 80 10, stiffened as described, and cut away at *2 3*, combined with the shoulder-straps, umbilical supporter, and buttons or fastenings to support from the back-pieces other garments, all substantially as described.

4. The shoulder-straps shaped as shown in cross-section, and having the thin flexible inner edges, *7*, as and for the purpose described.

In testimony whereof I have signed my name to this specification in the presence of 90 two subscribing witnesses.

ROBERT W. GRAY.
